UNITED STATES PATENT OFFICE.

CHARLES WILLIAM MALLINS, OF LIVERPOOL, ENGLAND.

TRAM-CAR.

1,104,813.

Specification of Letters Patent. Patented July 28, 1914.

Application filed January 21, 1913. Serial No. 743,378.

To all whom it may concern:

Be it known that I, CHARLES WILLIAM MALLINS, a subject of the King of Great Britain, and residing in Liverpool, England, 5 have invented certain new and useful Improvements in Tram-Cars, of which the following is a specification.

This invention relates to tramcars, and the object is to so modify the construction 10 of a double deck bogie car as to provide for separate exits and entrances, whereby passengers boarding the car or ascending to the upper deck, are kept quite distinct and apart from the passengers leaving the inside or 15 descending from the upper deck; whereby the seating accommodation for a given size of car is utilized to the fullest possible extent; and whereby the opposite ends of the car are quite symmetrical; and so that the 20 entrances and exits are separately located on the near side in whichever direction the car is running.

The invention also comprises certain improvements in devices to deter or caution 25 passengers from boarding or leaving the car when the latter is in motion, or after the signal has been given to the driver to proceed.

The invention is illustrated in the accompanying drawings in which—

Figures 1 to 6^B show the general arrangement of the car, and Figs. 7^A to 11 show details of the signaling devices. Fig. 1 is an elevation; Fig. 2 a plan in section on the line II, II, of Fig. 6^B, showing the seating and platform arrangements of the upper deck; Fig. 3 is a plan in section on the line III, III, of Fig. 1 showing the seating and platform arrangement of the lower deck; 40 Fig. 4 is a transverse section on the line IV, IV, of Fig. 1; and Fig. 5 is a transverse section on the line V, V, of Fig. 1. Figs. 6, 6^A and 6^B are views to a larger scale showing the arrangement of the main platform; 45 Fig. 6 is an elevation; Fig. 6^A is a plan, and Fig. 6^B is a transverse section on the line VI, VI, of Fig. 6. Fig. 7 is a detail of the signal arm.

The arrangements of the bogie trucks, 50 wheels, brakes, motors and controllers may be of any type suitable for the construction

of body about to be described, and are in general omitted from the drawings; the life-guard is preferably that known as the "Liverpool" type. 55

The main body of the car extends for nearly the whole length of the car leaving a driving platform A at each end, over which platform the upper deck B extends, said platform being open at the sides, or 60 being inclosed, as may be desired. The central portion of the main body C, C', is divided off from the interior, and forms a central platform D by which passengers board or leave the car. Two stairways are provided, having the inside stringers set at an angle with the tread, and from the central platform to the upper deck, one F an ascending stairway for those boarding, and the other E a descending stairway for those 70 leaving. The side opening of the platform D, which is provided with a suitable step d¹, is divided by two vertical posts d² and d³ into three parts, a central entrance and two laterally arranged exits. 75

The inside of the car is divided by the central platform into two compartments, the smaller of which C, may be adapted for first class passengers and the larger C' for ordinary passengers. The entrance to each compartment is by double door-ways c¹, c² and barriers are arranged so that passengers boarding the car by the central entrance are, in consequence of the barrier, compelled to enter the inside of the car by the off-side half of the doorways, or to ascend to the upper deck by the off-side stairway F; whereas passengers alighting must leave the car by one or other of the side exits, being directed thereto from the near side 80 half of the doorways of the inside compartments, or by the descending staircase E from the upper deck. It will be seen that for opposite directions of motion of the car, opposite sides of the platform are on the near side; the barriers referred to must therefore be so arranged that they can be swiveled so as to make the near side of the platform 85 form the entrance and exits in whichever direction the car is running; the offside of 90 the platform must of course be closed and this can be done by means of a balanced 95 100

guard rail, or the barriers may be arranged so that they can be used alternatively for directing the passengers on the near side and for closing-in the platform on the off-side. The preferred arrangement of the barriers is as follows:—The double stanchion d^4 is fixed opposite the meeting stiles of each pair of doors, and swiveling barriers d^7 and d^8 which may be ornamental iron work hinged doors are provided, and pivoted at d^5 and d^6 to the posts d^2 and d^3 as shown; when the car is traveling in the direction of the arrow Z, (Fig. 6^A), these barriers are arranged as shown in Fig. 6^A, so that they 10 form a central entrance and two side exits on the near side, and completely close in the off-side; when the car is running in the opposite direction to that indicated the arrangement of the barriers d^7 and d^8 is reversed. The seats G generally are arranged transversely, but are, of course arranged to fully utilize the space and some of them such as g^1 may be arranged as drop seats so as to give clearance space when desired. The 20 whole of the upper deck is closed in by the roof H, and the stairways E and F are accordingly fully protected. Doors a^1 are provided at the end of the two lower deck compartments to give access to the driver's platform forms A. With this arrangement, a car having an over-all length of 35 feet may be arranged to have a total seating capacity for 25 eighty-four passengers.

The arrangement of barriers and entrances to the lower deck compartments and the arrangement of the stairways and seats, may of course be modified within the limits of my invention to meet any special cases.

The location of the platform in an approximately central position, as described has the advantages that the platform is protected from the weather; that all passengers boarding or leaving the car are brought to a focus under the control of the conductor; 45 that the weight of passengers assembled on the platform is evenly distributed; as distinguished from the case of cars with end platforms, when the weight of passengers assembled on the rear platform tends to tilt 50 the car.

The car body is carried on a gap frame to permit of the platform being arranged several inches below the car floor, to reduce the height of the step.

55 In order to deter passengers from attempting to board or leave the car when it is in motion, or after the signal has been given to the driver to proceed, light arms O may be mounted on the vertical posts d^2 , d^3 at the entrance and exits so that in one position they extend across the entrances and exits, and in the other position are clear of them. The arms (see Figs. 7 and 6) are preferably

pivoted on sleeves o^1 on the vertical posts d^2 , d^3 , and suitable pulleys o^2 on the sleeves are 65 connected to a spring o^3 which normally holds the arms in the clear position. The pulleys are also connected by cords o^4 to a lever o^5 operated by an electromagnet o^6 energized by a generator o^7 driven from the 70 car wheels, so that when the car is in motion the electro-magnet is energized and draws the arms into the obstructing position. In a similar manner, the pulleys are also connected by a cord to a lever o^8 operated by the 75 conductor in such manner that when he signals the driver to proceed, the arms are drawn into the obstructing position and that when he signals the driver to stop, they are turned from the obstructing position 80 when the car comes to a stand; the said lever may operate the signal bell through a dash pot arrangement so as to give a time interval.

The cars are fitted with balanced windows 85 and ventilators.

It is convenient to have the entrance at the center and the exits at the sides of the platform, the entrances may however be at the sides and the exit at the center in which 90 case E would be the ascending stairs and F the descending stairs.

Having now fully described my invention, I declare that what I claim and desire to secure by Letters Patent is:—

1. In a double decker tramcar in combination:—a central platform dividing the lower deck into two compartments; a doorway from each compartment to the platform; two separate stairways from the platform 100 to the upper deck; two stanchions dividing the side entrance to the platform into two wing sections and one central section; barriers extending respectively from opposite the center of each of the doorways to the adjacent stanchion, one of the said barriers dividing off a portion of the platform which 105 communicates with one half of one of the doors, one of the staircases and one of the wing sections of the side entrance, and the other barrier dividing off a portion of the 110 platform which communicates with one half of the other door and the other wing section of the side entrance, the remaining portion of the platform communicating with 115 the other staircase and the other halves of the two doors; substantially as described.

2. In a double decker tramcar in combination:—a central platform dividing the lower deck into two compartments; a doorway 120 from each compartment to the platform; two separate stairways from the platform to the upper deck; two stanchions on each side of the platform dividing each side entrance to the platform into two wing sections and 125 a central section; two barriers one opposite

the center of each of the doorways; two pivoted barriers on each stanchion adapted when extended to completely close the said entrance, and when folded together to connect the respective barriers to the respective stanchions; substantially as described.

In testimony whereof, I affix my signature in presence of two witnesses.

CHARLES WILLIAM MALLINS.
